ABSTRACT: A pan carrier assembly for storing and transporting fabric samples and the like, including plural pans forming open receptacles for containing the samples and having a flange rim about the pan opening, and a carrier frame for supporting pairs of the pans in aligned confronting relation. The carrier frame has two oppositely opening wells into which the flange rims nest, and retaining formations for releasably holding the pans in assembled relation on the carrier frame.

SHEET 2 OF 2

PAN CARRIER ASSEMBLY FOR FABRIC SAMPLES

BACKGROUND AND OBJECTS OF THE INVENTION

Heretofore, transporting containers for carrying fabric samples, textiles and the like on sales calls have frequently been in the form of conventional luggage cases having the usual two case sections hinged together, and sometimes having rack mechanisms within the case sections. An object of the present invention is the provision of a novel system for transport and storage of fabric samples to be shown by salesmen to prospective buyers, wherein basic units in the form of plastic pans provide receptacles for the fabric samples and may be readily assembled into carrier frames of either two or four pan capacity for transport on a sales call. The pan may be packed with portions of the fabric line in accordance with the salesman's wishes and may be stored in a salesman's desk or other storage facility in a form similar to pullout drawers, or may be rapidly assembled in various combinations in the carrier frames to provide a variety of portions of the line depending on the anticipated needs of the particular sales call. Thus, great flexibility is provided as well as improved convenience in storage of the sample containing pans, avoiding many of the disadvantages attendant to the use of conventional luggage cases for transporting such samples.

Other objects, advantages and capabilities of the present invention will become apparent from the following detailed description, taken in conjunction with the accompanying drawings illustrating preferred embodiments of the invention.

BRIEF DESCRIPTION OF THE FIGURES

FIG. 1 is a perspective view of a pan carrier assembly, illustrating a first embodiment of the present invention adapted to carry two pans;

FIG. 2 is a perspective view of the two-pan carrier frame, with the pans removed;

FIG. 3 is a vertical section view taken along the line 3-3 of FIG. 1;

FIG. 4 is a perspective view of a pan carrier and pan assembly adapted to carry four pans; and

FIG. 5 is an exploded fragmentary perspective view illustrating the details of construction of the safety release mechanism.

DETAILED DESCRIPTION OF PREFERRED EMBODIMENTS

Referring to the drawings, wherein like reference characters designate corresponding parts throughout the several FIGS., the pan carrier assembly of the present invention, indicated generally by the reference character 10, is designed to facilitate transportation by salesmen of a plurality of pans, indicated at 11, forming upwardly opening traylike receptacles for storing a plurality of fabric samples. The pans 11 are preferably vacuum formed plastic pans, of a size about 12×16×3 inches, each having a bottom panel 12, side walls 13, and outwardly projecting peripheral flanges 14 at the edges of the sidewalls opposite the edges joined to the bottom panel. These pans 11 may be formed of styrene sheet material or other well-known plastic sheet material by the process customarily employed in vacuum forming molded plastic shells to be used as luggage case sections and similar receptacles. It will be appreciated that the plastic material is somewhat flexibly deformable so that a limited amount of inward flexing of the flange portions at least along the midregion of each flange can be effected.

These pans 11 can be used in two principal ways. They can be stored in quantities at each salesman's desk in the manner of a pullout drawer, either prepacked with selected portions of the fabric line or packed by the salesman or under his direction prior to a scheduled visit or series of visits to contain the portions of the fabric line which the salesman wishes to display. Alternatively, the pans 11, after being packed with the desired fabric samples, can be assembled into the carrier frames as hereinafter described, of either the two or four pan

capacity, for transport on a sales call as a suitcase. Thus, can a salesman rapidly assemble a variety of portions of the fabric line depending on the anticipated needs of the particular sales call.

5 The carrier frame of the two-pan capacity is indicated at 15 in FIGS. 1 and 2 and includes an upright, generally rectangular framed panel section 16 having frame members 17, 18, at the opposite vertical edges thereof and frame members 19 and 20 at the upper and lower horizontal edges. Each of the frame members is formed of elongated metallic members, such as metallic extrusions, having a T-shaped cross section providing a central web portion 21 and oppositely directed flanges 22, 22a lying in a common plane perpendicular to the plane of the web portion 21. These frame members 17-20 are preferably of anodized metal wherein the height of the web portion 21 in the vertical plane is one-half inch and the maximum horizontal width of the flange portions 22, 22a is 1½ inch. The web portion 21, which forms the thick vertical leg of the T may be three-eighths inch thick, and the flanges may be one-eighth inch thick. Assembled onto the opposite lateral surfaces of the web portion 21 of the frame members are a pair of sheet metal panels 23, 23a fastened to the surfaces of the web portion 21 in any suitable manner, as by adhesives, countersunk screws, or other conventional fastening members. A pair of footing members 24 are secured to the lower end portions of the vertical frame members 17, 18 and project a substantial distance outwardly from the vertical center plane of the pan carrier frame, for example, about 3¾ inches, to rest on a horizontal surface and support the framed panel section 16 in a vertical plane. The outer end portions of the footing members 24 may have channel-shaped rubber pads or feet 24a to engage the supporting surface.

35 The flanges 22, 22a and panels 23, 23a define two oppositely opening shallow wells of a size corresponding to the flanged portions of the pans 11 to accommodate the flanges 14 of one pan in nested relation within each well, as indicated in FIG. 1. Bottom retaining lips are provided at the lower corners of each well by channel members 25 having a web or base 25a about 1 inch wide and channel sides 25b projecting upwardly about one-half inch through recesses 20a in the opposite end portions of the lower horizontal frame member 20. The web or base portions 25a of these channel members 25 are secured against the lower surface of the flange portions 22, 22a of the frame member 20 by any suitable fastening means, such as the screws 25c.

40 A latching member 26 is provided in the midregion of the upper frame member 19, and is also formed of a channel having a web 26a about 1 inch wide overlying the flange portion of the top frame member 19 and having downwardly projecting channel sides or flanges 26b extending about three-fourths inch downwardly from the web portion through elongated recesses 19a in the opposite flanges 22, 22a of the top frame member 19. The latching member 26 is pivotally supported by spindle 27 which extends through a suitable bore in the web portion 21 of the top frame member 19 and is resiliently biased to a downward or latching position by coil spring 28 compressed between the lower end of the web portion of frame 19 and a shoulder, formed for example by a washer 27a retained on the spindle 27 by retaining pin 27b, such as a cotter pin or the like.

45 The extent of axial movement of the spindle 27 is such that the channel portion of the latching member 26 can be raised to clear the lower edges of the channel side flanges 26b above the flanges of frame member 19 and free the latching member 26 to be rotated to an angular release position relative to the frame member 19 with the lower edges of the channel side flanges 26b resting on the top surface of panel member 19. 50 The upper edge portions of the pan 11 must then be manually depressed downwardly through a short distance, for example, about one-eighth inch, to clear the upper edge of the uppermost flange 14 below the nose of the substantially triangular strike formation 29 at each end of each of the recesses 19a. The pans 55 can then be lifted to withdraw the flanges 14 along the lower

edge of the pans from behind the channel side flanges 25b of the channel members 25 for complete withdrawal of the pans from the carrier frame 15. To reassemble a pan with the carrier frame, the flange 14 at the lower edge of each pan is inserted between the channel side flanges 25b and the panels 23, 23a and, with the latching member 26 raised to the release position, the pans are swung inwardly about their lower edges toward the framed panel section 16 until the edges of the upper flanges 14 engage in and are cammed downwardly by the inclined surfaces of the strikes 29 and pass between the strikes 29 and the panels 23, 23a, whereupon the uppermost flanges 14 snap upwardly to be retained in these spaces.

As illustrated in FIG. 1, a conventional U-shaped handle 30 is also secured to the top frame member 19, the legs of the handle 30 being disposed, for example, in flanking relation to the latching member 26.

The four-pan carrier frame is illustrated in FIG. 4 and indicated by the reference character 35. Its construction is substantially the same as the two-pan carrier, except that the framed panel section, here designated by the reference character 16', includes T-shaped frame members 17', 18', 19', and 20' of the same cross section as the frame members for the two-pan carrier frame, and panels 23', 23a' defining two oppositely opening wells each sized to receive the flanges 14 of two of the pane 11. Thus, for pans wherein the perimeter defined by the free edges of the flanges 14 are 16 inches by 12 inches, the wells defined by the frame members 17'-20' and panels 23', 23a', may each have a height slightly over 16 inches and a width slightly over 24 inches to accommodate two pans 11 in side-by-side fashion as illustrated in FIG. 4. Because of the relatively long expanse between the vertical frame members 17', 18', a spacer of styrofoam or other material, indicated at 36 and extending from the midregion of the bottom frame member 20', to the midregion of the top frame member 19', is provided between the panels 23', 23a', to maintain the two panels in properly spaced relation. Bottom retaining lips are defined at the two lower corners of the wells by channel members 25 of the same construction as described in connection with the preceding embodiment, and an additional bottom retaining channel member 25' is provided at the longitudinal center of the bottom frame member 20 assembled to the frame in the same manner as the channel members 25, but wherein the horizontal longitudinal extent of the channel member 25' is approximately twice that of the channel members 25. Also, a pair of latching members 26' are associated with the top frame member 19' in the same manner as the latching member 26 is associated with the top frame member 19 in the preceding embodiment, and are located substantially midway between the handle 30' and the opposite ends of the top frame member 19' so as to releasably latch the uppermost flange 14 of the pans 11.

We claim:

1. A pan carrier assembly for storage and transportation of fabric samples and the like, comprising a plurality of pans for containing the samples, each pan being a concave traylike shell of flexibly deformable material defining an open receptacle when removed from the assembly having a substantially planar base wall and sidewalls extending integrally therefrom terminating in outwardly directed flange portions collectively forming a substantially rectangular flange perimeter framing the receptacle opening, and a carrier frame having a handle formation thereon for removably supporting and transporting a plurality of said pans in aligned pairs with their openings facing each other, the carrier frame comprising panel means defining a pair of oppositely facing rectangular planar abutment surfaces paralleling a medial reference plane of the frame, frame members circumscribing the four edges of said surfaces forming rim flanges projecting outwardly therefrom and defining therewith a pair of oppositely facing shallow wells each sized to receive the flange perimeter of at least one of said pans nested therein, first retaining lip members protruding inwardly into each well from a first one of the frame members bounding the same to outwardly lap and

retain a corresponding flange portion of the pans against the abutment surfaces of the associated wells, and second retaining lip members movably supported on a second one of the frame members spaced from said first lip members for selective movement to a holding position protruding into each well in outwardly lapping and retaining relation to another flange portion of the pans against said abutment surface and to a release position withdrawing the same from such lapping relation to free the pans for removal from the carrier frame.

5 10 2. A pan carrier assembly as defined in claim 1, wherein said panel means comprises a pair of rectangular sheet material panels spaced in symmetrical parallel relation on opposite sides of said medial reference plane of the carrier frame, and spacer formations disposed between at least the marginal portions of said panels maintaining them in uniform spaced relation.

15 20 25 3. A pan carrier assembly as defined in claim 2, wherein said frame members each comprise an elongated rectilinear structural member of T-shaped cross section having a central web portion extending between the margins of said panels and forming said spacer formations and oppositely projecting flange portions forming said rim flanges projecting perpendicular to said reference plane and outwardly beyond said surfaces a distance slightly greater than the thickness of the flange perimeter of said pans.

4. A pan carrier assembly as defined in claim 3 wherein said rim flanges of said second frame member lie in a common plane perpendicular to said reference plane, and said second 30 35 retaining lip members being formed of a U-shaped elongated channel having a web portion located outwardly adjacent said second frame member and a pair of channel side flanges extending integrally from the web portion toward the center of the carrier frame, said second frame member having recesses

35 40 45 50 55 60 65 70 75 in the rim flanges thereof accommodating passage of said channel side flanges therethrough into said lapping relation to the flange perimeters of said pans when said channel is longitudinally aligned with said second frame member, and resiliently biased spindle means supporting said channel for rotary movement about a spindle axis perpendicular to said common plane and for axial movement along the spindle axis to permit selective withdrawal of the channel side flanges from said recesses and from said lapping relation and rotation of the channel to an angular position relative to the second frame member.

5. A pan carrier assembly as defined in claim 2 wherein said rim flanges of said second frame member lie in a common plane perpendicular to said reference plane, and said second retaining lip members being formed of a U-shaped elongated channel having a web portion located outwardly adjacent said second frame member and a pair of channel side flanges extending integrally from the web portion toward the center of the carrier frame, said second frame member having recesses in the rim flanges thereof accommodating passage of said channel side flanges therethrough into said lapping relation to the flange perimeters of said pans when said channel is longitudinally aligned with said second frame member, and resiliently biased spindle means supporting said channel for rotary movement about a spindle axis perpendicular to said common plane and for axial movement along the spindle axis to permit selective withdrawal of the channel side flanges from said recesses and from said lapping relation and rotation of the channel to an angular position relative to the second frame member.

6. A pan carrier assembly as defined in claim 1, wherein said frame members each comprise an elongated rectilinear structural member of T-shaped cross section having a central web portion connected to and supporting said panel means and oppositely projecting flange portions forming said rim flanges projecting perpendicular to said reference plane and outwardly beyond said surfaces a distance slightly greater than the thickness of the flange perimeter of said pans.

7. A pan carrier assembly as defined in claim 6 wherein said rim flanges of said second frame member lie in a common

plane perpendicular to said reference plane, and said second retaining lip members being formed of a U-shaped elongated channel having a web portion located outwardly adjacent said second frame member and a pair of channel side flanges extending integrally from the web portion toward the center of the carrier frame, said second frame member having recesses in the rim flanges thereof accommodating passage of said channel side flanges therethrough into said lapping relation to the flange perimeters of said pans when said channel is longitudinally aligned with said second frame member, and resiliently biased spindle means supporting said channel for rotary movement about a spindle axis perpendicular to said common plane and for axial movement along the spindle axis to permit selective withdrawal of the channel side flanges from said recesses and from said lapping relation and rotation of the channel to an angular position relative to the second frame member.

8. A pan carrier assembly as defined in claim 7, wherein said carrier frame includes a pair of footing members secured to an opposite pair of said frame members and projecting in opposite directions from said reference plane to support said carrier frame and a horizontal surface with the planes of said abutment surfaces disposed in vertical planes and said first and second frame members arranged as bottom and top horizontal frame members, respectively.

9. A pan carrier assembly as defined in claim 1 wherein said rim flanges of said second frame member lie in a common plane perpendicular to said reference plane, and said second retaining lip members being formed of a U-shaped elongated channel having a web portion located outwardly adjacent said second frame member and a pair of channel side flanges extending integrally from the web portion toward the center of the carrier frame, said second frame member having recesses in the rim flanges thereof accommodating passage of said channel side flanges therethrough into said lapping relation to the flange perimeters of said pans when said channel is longitudinally aligned with said second frame member, and resiliently biased spindle means supporting said channel for rotary movement about a spindle axis perpendicular to said

common plane and for axial movement along the spindle axis to permit selective withdrawal of the channel side flanges from said recesses and from said lapping relation and rotation of the channel to an angular position relative to the second frame member.

10. A pan carrier assembly as defined in claim 9, wherein said rim flanges of said second frame member include strike formations projecting therefrom toward the center of said wells each providing a shoulder confronting one of said abutment surfaces and spaced therefrom approximately the thickness of said flange perimeter of said pans to lap a flange portion of said flange perimeter and retain the same against the adjacent abutment surface, and said strike formations presenting an inclined surface to said flange perimeter approaching movement of the latter toward nested position within said wells to engage and cam a flange portion of the pans in a direction to pass the strike formations and interfit between said shoulder and one of said abutment surfaces.

11. A pan carrier assembly as defined in claim 1, wherein said carrier frame includes a pair of footing members secured to an opposite pair of said frame members and projecting in opposite directions from said reference plane to support said carrier frame and a horizontal surface with the planes of said abutment surfaces disposed in vertical planes and said first and second frame members arranged as bottom and top horizontal frame members, respectively.

12. A pan carrier assembly as defined in claim 1, wherein said rim flanges of said second frame member include strike formations projecting therefrom toward the center of said wells each providing a shoulder confronting one of said abutment surfaces and spaced therefrom approximately the thickness of said flange perimeter of said pans to lap a flange portion of said flange perimeter and retain the same against the adjacent abutment surface, and said strike formations presenting an inclined surface to said flange perimeter approaching movement of the latter toward nested position within said wells to engage and cam a flange portion of the pans in a direction to pass the strike formations and interfit between said shoulder and one of said abutment surfaces.
